CARBURETING MECHANISM FOR GAS-ENGINES.

1,172,258.

Specification of Letters Patent. Patented Feb. 22, 1916.

Application filed October 19, 1910. Serial No. 587,891.

To all whom it may concern:

Be it known that I, JOSEPH C. COULOMBE, a citizen of the United States, and a resident of Northfield, in the county of Washington 5 and State of Vermont, have invented certain new and useful Improvements in Carbureting Mechanism for Gas-Engines, of which the following is a full, clear, and exact description, whereby any one skilled in the art 10 may make and use the same.

The invention relates to a carbureting mechanism for explosive engines and more particularly to a device for securing proper admixture of a volatile explosive substance.

15 The objects of the invention are to provide a mechanism for securing as complete volatilization of the oil or other substance to be utilized for forming an explosive mixture as will secure proper combustion of the 20 mixture.

25 A further object is to control the effective action of the vacuum created by the suction of the engine in such manner that the fluid drawn to the engine due to the vacuum will always be impregnated to the proper degree with the materials forming the explosive mixture.

30 A still further object is to control the suction draft of the engine with reference to the carbureting device, in such manner that there will be a constant and uniform flow of fluid through the mechanism irrespective of the variations in suction.

35 Referring to the drawings:—Figure 1 illustrates the mechanism as applied to an engine cylinder. Fig. 2 is a central sectional view of the controlling device intermediate the engine cylinder and carbureting mechanism. Fig. 3 is a detail cross-sectional view of a mixing valve such as illustrated with the controller in Fig. 1. Fig. 4 is a view in side elevation with parts broken away illustrating the controller applied to an ordinary float-feed carburetor. Fig. 5 is 45 a perspective view of one of the cones of the controlling device.

In practice, many forms of carbureting mechanisms have been utilized including the so-called carburetors in which the oil or volatile fluid is drawn off by the suction of the engine as it pulls varying volumes of air across the fluid nozzle and including the so-called mixing valves in which the fuel ori-

fice is closed by a valve which is subject to change of position upon variations in the 55 suction effect of the engine. It has also been a practice to utilize compensating mechanisms for carburetors for varying the quantity of air with reference to the suction effect of the engine and consequently vary 60 the quantity of volatile fluid taken up by said suction. In all such devices, the suction of the engine is necessarily variable dependent upon its speed and therefore the operation of the carbureting mechanism has been 65 more or less uncertain due to extreme changes of suction.

It is the primary object of the invention to overcome the objections of improper operation due to uneven and varying suction of 70 the engine by providing a means intermediate the fuel supply and air inlet and the engine cylinder for obviating variable and undue suction of the engine by controlling said suction. It is believed this has not been 75 practically done heretofore, in as much as variations in suction due to the variations in speed of the engine and the consequent passage of varying volumes of fluid through the carbureting mechanism in a given period 80 of time has necessarily subjected the carbureting mechanism to abnormal conditions, resulting in improper mixture of the air and liquid fuel. In the device herein described, the suction itself is controlled with a result 85 in the carbureting device.

It is of course apparent that an engine cylinder having a given bore and stroke requires a given volume of explosive mixture 90 to fill the cylinder and it is the object of the present invention to provide the proper volume of mixture for the cylinder without creating great variation in suction through the carbureting mechanism. Gases under 95 pressure expand uniformly and in all directions when released, and it is assumed in the mechanism hereinafter described that the incoming gases, being released by the formation of a partial vacuum, likewise expand as hereinafter defined, as soon as they enter the chamber in which the partial vacuum has been induced.

In the accompanying drawings, the numeral 1, denotes a cylinder of a gas engine 105 which, of course, is provided with a piston,

inlet and exhaust valves, and mechanism ordinarily employed for controlling the operation of said parts including an ignition device.

5 The several parts of the engine are not herein specifically shown and described as such devices are well known in the art and the mechanism hereinafter defined may be applied to the various types of gas or liquid hydro-carbon engines.

As illustrated in the drawings, in Fig. 1, the cylinder is provided with an inlet 2, and an exhaust 3. The inlet 2, as shown in Figs. 1 and 3, is connected with a carbureting device of the mixing valve type illustrated at 4, and in the connection between the mixing valve and the inlet valve of the cylinder is arranged the controller 5. The mixing valve, as shown herein, comprises a casing 6, having an air inlet 7, and an outlet 8. An oil nozzle or a fuel nozzle 9, extends within the chamber 10, of the mixing valve and is controlled by a needle-valve 11, connected with a baffle-plate 12, which divides the chamber 10, from the chamber 11^a. The outlet 8, is in connection with the chamber 10, through an adjustable passage 13, and through the valve opening 15, controlled by the baffle-plate 12, when the latter is raised.

20 30 The passage-way 13, is controlled as to its area by a plate 14, actuated by a thumb-nut 15^a, and locked in position by a lock-nut 16, mounted upon a threaded spindle 17. The needle-valve 11, with its baffle-plate 12, may be adjusted for various degrees of movement by a stud 18, terminating in a thumb-nut 19, and bearing an indicator finger 20. The adjustment of the stud 18, determines the throw of the valve 11, with its plate 12.

40 45 In such a device, the ordinary suction of the engine raises the plate 12, and with it the needle-valve 11, permitting the liquid fuel to pass through the nozzle 9, from the supply connection 20. In order to compensate for the variations in speed, the passage way 13, is provided, and thus a certain portion of air entering the chamber 10, through the inlet 7, will pass by the nozzle 9, and through the passage 13, becoming mixed with the fluid which has passed up through the opening 15, and carried with it a certain amount of the liquid fuel. Such a mixing valve as above described is not new in the art.

55 60 65 In Fig. 4, the controller is illustrated in connection with a float-feed carbureter of the ordinary type in which there is a casing 25, provided with a float-feed chamber 26, and a carbureting chamber 27. The air inlet to the carbureting chamber 27, is illustrated at 28, adjacent to the fuel nozzle 29, which is in direct connection with the float-feed chamber 26, through a passage 30. A float-feed 31, controls the inlet valve 32, which connects the float-feed chamber 26,

70 75 80 85 90 95 with the supply-pipe 33. The mechanism is so adjusted that a constant level is maintained in the oil nozzle 29, and a valve 34, controls the nozzle 29. Suitably mounted upon the casing is the lever 35, which controls a suitable throttling valve 36, for throttling the mixture which is sucked in by the engine. The controller 5, is illustrated as extending from the outlet side 37, of the carbureter and of course has proper connection with the engine cylinder. In either of these devices, the mixing valve shown in Figs. 1 and 3 or the float-feed carbureter illustrated in Fig. 4, it is the object to pick up the proper amount of liquid fuel with the air which is brought in through the carbureter. In all such devices, the variations in suction due to the variations in speed of the engine cause an improper action of the carbureting mechanism, and the mixture secured with a certain adjustment of the devices, may be too "rich" or too "poor" to give the best results. To overcome these objections, a controller is interposed between the carbureter or mixing valve and the intake valve of the engine as illustrated in the drawing. This controller consists of a casing shown herein as of tubular form and provided interiorly with a series of cone-like members 38, nested together within the casing 39. The cone-like members 38, when nested together, form independent chambers 40, each of said chambers having their side-walls extending at an angle from the central axis of the device.

necessary quantity of vapor through the controller at all times.

It is apparent that the greater the vacuum caused by the suction of the engine, the greater the speed of the column of gas will be and the more rapidly and more certainly the heavier particles will be thrown into the chambers, in as much as the gas under the pressure will expand in all directions. The effect is for each of the succeeding cones to take off a portion of gas from the passing column which portion, of course, will contain the less attenuated mixture. For instance, when running at low speeds, a partial vacuum is formed in the controller and each of its chambers by the gradual exhaustion of the fluid. At the same time, there is a suction effect upon the carbureting mechanism. As the engine varies its speed or suddenly increases its speed, the vacuum is more pronounced. Thereupon, there is a greater tendency for vapor or gas to expand into the vacuum chambers. The heavier gases bearing the richest amount of liquid fuel are naturally thrown to the outside and away from the central line of movement of the gases and if these particles are sufficiently heavy, they will ultimately be forced backward and out into the open channel through the central line of the device, being there picked up by the more rarified gas and successively thrown into the several chambers. With this device, a sudden impulse or increase in the suction due to sudden increase in speed of the piston will not be effective to cause flooding of the carburetor and the drawing up of a greater quality of fuel than is required to secure the proper explosive mixture. If the carbureting mechanism is once properly adjusted, it needs no further attention as the effect of the controller is to give a gradual and uniform passage of vapor of the proper attenuation, even upon varying speeds of the engine. By creating a partial vacuum throughout the chambers of the controller, it follows that there is a constant and even draft through the carburetor, and even if the mixture becomes too rich upon entrance to the controller, the expansion of the gases will throw off the heavier particles until they are gradually picked up by the moving column of vapor. It has been found from actual experiments that the mixture thus secured is a very perfect mixture, in as much as the combustion is complete and the exhaust from the engine shows no appreciable sootting or passage of unconsumed fuel even under varying conditions of load and speed. This is attributed to the theory of operation above defined, which causes the oils of more or less volatile nature to be completely and thoroughly taken up by the inflowing air, in such manner that the current of air instead of being drawn in in

varying volumes with more or less forceful impulse, is constantly passing through the controlling device and throwing off or taking up the particles of oil until the proper degree of saturation is attained.

Obviously the details of the device might be varied to a considerable extent and while it is shown herein of cylindrical form, this form might be varied without departing from the spirit or intent of the invention. Furthermore, the number of chambers and the tapering of the cones forming the several chambers, together with the size of opening therethrough may be varied to suit the exigencies of any particular case.

What I claim as my invention and desire to secure by Letters Patent is:—

1. In a vaporizer having a vapor inlet and a fluid supply coöperating therewith and to be vaporized by the passage of vapor through the inlet and an outlet for the vaporized fluid connected with a suction device, means for maintaining a substantially constant mixture of fluid and vapor through said device upon varying conditions of suction, said means including a series of chambers intermediate the outlet side of the vaporizer and the suction device, each chamber having its walls imperforate and tapered toward a common central axis and each chamber having its inlet projecting within the preceding chamber.

2. In a vaporizer embodying an air inlet, a fluid supply to be mixed therewith and an outlet, a cylindrical casing extending from the outlet and having arranged therein a series of chambers, each chamber having imperforate walls and each chamber opening to a common central orifice connecting all of said chambers, the inlet of each chamber arranged within the next preceding chamber of the series, the chambers forming individual expansion chambers arranged in series to receive the fluid passing through the vaporizer and successively subject to suction whereby the speed of the fluid is controlled.

3. In combination with a vaporizer for an engine or the like, means intermediate said vaporizer and engine for controlling the speed of movement of the fluid through said vaporizer, said means embodying a series of annular chambers formed with imperforate tapered members nested one within the other and with their walls substantially parallel, all of said chambers being closed except for a central opening common to all of said chambers, the central opening to each chamber located within the annular walls of the next preceding chamber of the series.

4. In combination with a vaporizer for an engine or the like, actuated by the suction of said engine, a cylindrical casing intermediate said vaporizer and engine, said casing con-

taining a series of conical imperforate walls arranged parallel to each other and extending toward the central axis of the casing, said walls having a common central opening therethrough arranged co-axially with the axis of the casing and with the central aperture of each of the succeeding walls gradu-

ally decreasing in diameter from the inlet toward the outlet of the casing.

JOSEPH C. COULOMBE.
